UNITED STATES PATENT OFFICE.

WILLIAM HUBBARD, OF HERKIMER, NEW YORK, ASSIGNOR TO WILLIAM HUBBARD AND FRED A. RAY, A PARTNERSHIP, OF HERKIMER, NEW YORK.

ATTACHMENT FOR DIEING-OUT MACHINES.

Application filed June 24, 1924. Serial No. 722,145.

This invention relates to improvements in dieing-out machines and is more particularly directed to an attachment for such machines providing an automatic stock feeding and blank cutting device.

It is an object of this invention to provide an attachment for dieing-out machines to automatically cut blanks from a roll of material and including an improved means for feeding the stock to the cutters.

Another object of this invention is to provide an attachment for dieing-out machines to automatically cut blanks from a roll of material and including improved means for feeding the stock to the cutters with additional means for adjusting the stroke of the feeding mechanism according to the size of the blanks being cut.

A further object of this invention consists in the provision of an attachment for sole cutting machines including improved means for intermittently feeding the stock to the cutters and means to automatically elevate the end of the stock above the cutters before the beginning of each feeding stroke.

Still another object of this invention consists in the provision of an improved attachment for dieing-out machines including means for intermittently feeding the stock, together with guides for the sides and top of the stock, and improved means for supporting the stock rolls.

A still further object of this invention consists in the provision of an improved double die for use in cutting blanks from sheet material on a dieing-out machine and having means for severing the waste to prevent clogging.

These and further objects will be more apparent from the following description taken in conjunction with the attached drawings, wherein:

Figure 1 is a front elevation of a dieing-out machine showing the improvement according to this invention in place;

Figure 2 is a longitudinal vertical section on line 2, 2, of Figure 1;

Figure 3 is a perspective view on an enlarged scale, certain parts being cut away to more clearly illustrate the die, the feed table and the guide means;

Figure 4 is a partial side elevation on an

enlarged scale, certain parts being broken away to more clearly illustrate the feed mechanism;

Figure 5 is a plan view of a portion of the feed table showing the feed block;

Figure 6 is a partial section on the line 6, 6 of Figure 4 illustrating the means of mounting the feed block;

Figure 7 is a transverse section through the die and die bed; and

Figure 8 is a partial vertical section on line 8, 8 of Figure 2.

It has been the custom in the cutting of blanks from materials such as felt for sole fillers, soles, heel seat fillers, uppers, etc., in the shoe manufacturing business to use a machine commonly known as a gear or gearless sole cutting machine and also known in the trade as a beam dinker or dieing-out machine. Such a machine usually includes a die bed support and a vertically reciprocating cutting plate or beam operated by the tripping of a clutch by pressure of the operator's foot upon a treadle. This method of cutting blanks involved the manual placing of the die upon the stock in various positions in order to economize in material, after which the clutch was tripped to force the die through the stock. This operation has always been considered very dangerous, and owing to the danger of mutilated hands has resulted in great difficulty in finding operators to work on these machines. Furthermore, this hand method of cutting blanks from a large sheet of stock involves cutting the stock into squares or rectangles from a large roll, resulting in considerable wastage at the edge of each rectangle.

This invention makes use of the same type of machine adding as an attachment means for fastening the die to the die bed and automatic means for intermittently feeding the stock from a continuous roll just the right distance after each stroke of the cutting plate to supply sufficient material for the blank or blanks to be cut at the next stroke. This involves only a wastage at one end of a large roll, usually of about one hundred feet and results in a great saving of material, while at the same time eliminating any necessity of manual operation of

the die except in the process of setting up the machine.

Referring to the drawings it will be noted that the machine comprises a pair of side frames 10 bifurcated at the bottom to provide the supporting legs 11 and connected together by the transverse members 12 to form a rigid framework to support the various moving parts of the machine. The machine is provided with a horizontal die-bed supporting plate 13 rigidly secured to the side frames and adapted to support the die-bed hereinafter referred to.

Mounted directly above the die-bed supporting plate is the rectangular plunger head or beam 14 supported and guided for vertical reciprocation by means of the four pitman rods 15 one at each corner thereof sliding in suitable guides such as 16 and 17 on the side frames 10. The pitman rods forming a pair on each side of the machine are connected together at the bottom by cross heads 18 which are adapted to be reciprocated in unison by means of the connecting rods 19 having the eccentric straps 20 operating on the eccentrics 21, mounted on the main shaft 22 arranged transversely of the machine and provided with suitable bearings in the side frames 10. The main shaft 22 is adapted to be driven from the pulley 23 connected in any desirable manner to the source of power. A clutch 24 is interposed between the pulley 23 and the shaft 22 and is adapted to be operated to connect these two parts together by means of pressure of the operator's foot upon the treadle 25 which is normally held elevated in such a position as to release the clutch by means of a spring 26.

All of the above parts forming the dieing-out machine are old and well known in the art and it will be readily understood that upon the pressure of the operator's foot upon the treadle 25 the plunger head 14 will be vertically reciprocated and that upon release of the treadle such motion will cease.

This invention contemplates the provision of a fixed die and automatic means for feeding the stock thereto from a roll, and for this purpose there is shown the die-bed holder 27 comprising a pair of vertically extending parallel side plates bolted as shown at 28 to the die-bed supporting plate 13. Upon the horizontal upper edges of these side plates is mounted the die-bed 29 restrained against movement transversely of the machine by means of the guide bars 30 bolted to the outside of the side plates 27 and projecting above the ends thereof. The die-bed 29 is of such a length as to snugly fit between and be engaged by the guide bars 30 and is prevented from movement longitudinally of the machine by means of the bolts 31 threaded into the side plates 27.

For the purposes of this specification

there is disclosed a die adapted to cut soles such as for felt slippers etc. It will be readily recognized that if a single die for cutting such an irregular shape were used that there would be considerable wastage of material between the narrow heel portions of the blanks and it has been found that by arranging two dies side by side and facing in opposite directions that the curve of the instep of each sole will correspond with the widened forward portion of the adjacent sole so that a single cutter may serve to sever a pair of oppositely directed sole blanks, and hence a die such as 32 is found desirable for use on this type of machine and here it will be noted that the central cutting edge 33 severs the two soles and forms a portion of one edge of each. It will also be noted that the outer edge 34 of the outer die has substantially the same contour for most of its length as the inner edge 35 of the inner die, and thus it will be seen that if the stock is fed from the right, as viewed in Figure 3, that after a cut the forward edge of the stock will have substantially the same contour as the edge 34 of the die, and it will only be necessary to feed it a distance sufficient to bring that edge exactly above the cutting edge 34 to obtain the maximum number of blanks from a given length of stock, and it will be seen that the distance the material is fed for each cutting stroke will be equivalent to the average width of the sole blank.

The die 32 is formed of one piece having the sharpened upper edges and the central openings 36 and 37 which taper outwardly in width toward the bottom in order that a blank cut may readily fall through without binding against the sides. The die-bed 29 is provided with corresponding holes below the dies in order that the blanks as they are cut may fall therethrough and drop into the conveyor trough 38 in pairs, that is, right and left, to be later removed by the operator.

The dies are provided with a flat bottom and are conveniently held upon the die-bed by means of the horizontal screws 39 passing through the vertically upstanding flanges 40, integral with the die-bed and entering holes 41 in the ends of the dies. This means of attachment allows for ready interchangeability of the dies when it is desired to change the size or shape of the blanks being cut. It will be understood that the roll of stock being fed to the dies is of substantially the same width as the overall length of the dies, but in order to avoid the possibility of spoiling any blanks the stock may be slightly wider, in which case there will be a continuous irregular strip formed upon either side throughout the process of cutting, and in order to prevent this strip from clogging the dies or the feeding means, there is provided a pair of transversely extending knives

42 upon the dies. These knives extend well beyond the edges of the stock and have their upper cutting edges in the same plane as the cutting edges of the main die in order to sever this waste material into short pieces equivalent in length to the distance the stock is fed for each cutting operation.

Directly above the dies the plunger head 14 supports the cutting plate 14', a cushion member 14" being interposed between these two parts. The lowermost position of the cutting plate at the end of the stroke is adjustable by mechanism on the machine (not shown) in order that it may just contact with the cutting edges of the die to sever the blank from the stock.

The stock is fed to the dies over a horizontal feed table 43 suitably mounted on and connected to a pair of brackets 44 bolted as 20 at 45 to the vertical edges of the side plates 27 on the side opposite from the feed trough 38.

For the purpose of supporting a roll of stock there is provided at the remote end of 25 the feed table 43 a pair of brackets 46 bolted to the feed table and having vertically extending arms 47 provided with channels 48, on their facing sides, and with holes 49 forming journals for the shaft 50 of a small roller 30 51 arranged just beyond the end of the feed table 43 and having its upper surface very slightly above the plane of the top of the feed table.

The roll of stock is adapted to be mounted 35 upon a rod 52 of a length to engage within the channels 48 so that it may be said to float therein with the weight of the roll of material supported upon the freely rotatable roller 51 so that the stock may be fed from underneath the main roll passing over the roller 51 and resting upon the surface of the feed table 43.

The plane of the top of the feed table 43 is slightly elevated above the plane of the cutting edges of the dies in order that the material may be fed forward over the dies without being hindered in its forward movement by catching upon the edges of the dies. In order that the material may be pressed 45 down against the dies by the cutting plate at the time of cutting, there is provided on the forward end of the feed table the movable flap or hinged portion 53 having its upper surface forming an extension of the 50 upper surface of the feed table, pivoted thereto about the rod 54 passing through the lugs 55 extending from the sides of the feed table and through the reinforcing ribs 56 on the bottom of the flap. In order to 55 maintain the flap in its proper normal position, it is provided with the arm 57, pivoted to one of the ribs 56, projecting downwardly therefrom and provided at its lower end with the rod 57' surrounded by a coil 60 spring 58. The rod 57' passes through and

the spring abuts against one arm of the L-shaped bracket 59 bolted to one of the side frames 10. The rod 57' is provided with the lock nuts 60 beneath the bracket 59 to limit the amount that the spring 58 70 will elevate the forward edge of the flap above the top of the feed table. It will be seen that this arrangement will serve to maintain the upper surface of the flap in any desired angular relation with the upper 75 surface of the feed table but will allow it to be depressed upon the application of pressure upon its surface.

This hinged flap serves two purposes. In the first place it supports the stock almost 80 to the cutting edge of the dies and holds the edge above the level thereof as previously explained in order to prevent catching of the edge of the stock against the dies during the feeding movement thereof. 85 Upon the downward movement of the plunger head to bring the cutting plate in engagement with the cutting edges of the dies to sever the blanks from the main sheet of the stock the inner edge of the cutting 90 plate first engages the stock resting on top of the hinged flap and forces the flap down until the stock rests upon the cutting edges of the dies. Further downward movement of the cutting plate severs the blanks from the sheet of stock and allows them to drop through into the trough 38. Immediately 95 upon the upward movement of the plunger head, pressure on the hinged flap is released and it returns to its normal position 100 elevating the forward edge of the stock above the dies, from the position it has been pressed into by the cutting action of the cutting plate, thus preparing it to be again fed forward ready for the next cut. 105

This machine is adapted for use with various widths of stock depending upon the extreme length of the dies used, and in order to maintain the material exactly central of the dies, in spite of the fact that 110 the roll has some freedom of longitudinal movement upon its supporting rod, the feed table is provided with a pair of adjustable side guides 61 extending longitudinally of the feed table and supported from a pair 115 of transverse bridge bars 62 arranged parallel to and above the surface of the feed table 43 and supported by means of the integral depending flanges 63 bolted to the sides of the feed table. These bridge bars are provided with longitudinal slots 64 adapted to slidably receive therethrough the shanks of thumb screws 65 which are threaded into the guide members 61. Interposed between the heads of the thumb screws 65 and the 120 top surfaces of the bridge bars 62 are the washers 66. It will be clear that upon loosening the pair of thumb screws connected to either one of the guides 61 it may be adjusted transversely of the feed table 125 130

43 and locked in the desired position by the tightening of the thumb screws rigidly clamping it against the under surface of the bridge bars. Riveted to the under surface 5 of the bridge bars 62 between the guides is the thin metal sheet 67 having an upturned end 68 facing in the direction of the roll of stock. This plate is parallel to and spaced above the top of the feed table 43 a distance 10 substantially equivalent to the thickness of the stock being fed and forms in effect a stock-feed cover plate since it is located directly above the feeding device, which will be later described. It extends substantially 15 from the rear of the guide members 61 to the joint between the feed table and the hinged flap and is of a width slightly less than the narrowest stock that will be used upon the machine. It will be clear that the 20 stock being fed from the roll rests upon the surface of the feed table 43 beneath the surface of the stock-feed cover plate 67 and between the inner edges of the guides 61, thus being restrained against movement in 25 any direction except longitudinally of the feed table.

The stock from the roll must be fed to and above the dies and this feeding action must be intermittent and in synchronism with the 30 motion of the plunger head, means being provided to retain the stock stationary during the actual cutting operation and for sufficient time thereafter to allow the hinged flap 53 to raise the forward edge of the 35 stock above the cutting edges of the die. For this purpose the stock is fed toward the die by means of a reciprocating block, the period of rest for the stock occurring upon the return movement of this feed block. As 40 best shown in Figures 2, 4 and 6 the feed block 69 comprises a block of metal having a flat upper surface 70 and longitudinally extending side flanges 71. The block is adapted to reciprocate in a longitudinal 45 opening 72 provided in the feed table so that its upper surface 70 is flush with the top of the feed table, the flanges 71 being guided between the lower surface of the feed table and a pair of L-shaped ways 73 bolted to the 50 under surface of the feed table.

The feed block is adapted to be reciprocated through linkage connected to the main drive shaft 22 of the dieing-out machine and for this purpose the shaft is provided with a 55 centrally located eccentric 74 having fitted thereto an eccentric strap and rod 75. To one of the cross members 12 of the machine frame is bolted the vertical bracket 76 which provides fulcrum points for two bell 60 crank levers 77 and 78 respectively. The eccentric rod 75 is pivoted to the lower vertical arm 79 of the bell crank lever 77 and the other or horizontal arm 80 of this bell crank lever is connected by a link 81 to the 65 horizontal arm 82 of the bell crank lever 78

whose upper vertical arm 83 is connected by means of the parallel links 84 one on either side thereof to the feed block. The arm 82 of the bell crank lever 78 is provided with a series of longitudinally spaced holes and the 70 end of the link 81 connected thereto is bifurcated and provided with a pin 85 passing through the arms thereof and adjustable into any one of the holes in the arm 82, in order to vary the effective length of the lever 75 arm.

The lower end of the link 81 is pivoted by means of a bolt 86 to an adjustable block 87 slidably mounted between the ways 88 of the arm 80 of the bell crank lever 77. The 80 block 87 is provided with an L-shaped member 89 adapted to slide along one face and the top of the arm 80 and secured to the block 87 by the bolt 86. This L-shaped member has a threaded aperture parallel to 85 its direction of sliding within the ways and through this threaded aperture is passed a threaded rod 90 having a hand wheel 91 on one end thereof. The hub of this hand wheel is provided with a groove, journaled 90 in a plate 92 fastened to the end of the bell crank lever. The bolt 86 is enlarged at 95 forming a bearing for the link 81 and a shoulder abutting the block 87. It will be seen that rotation of the hand wheel 91 will cause a longitudinal adjustment of the pivot point of the link 81 in respect to the fulcrum 100 of the bell crank lever 77, and this adjustment may be locked by tightening the nut 86 on the bolt 86, thus clamping the arm 80 between the blocks 87 and 89. This mechanism provides means for varying the length of the arm of the bell crank lever 77 to adjust the distance of movement of the feed block 69.

The parallel links 84 are adapted to reciprocate the feed block and also to project and retract the feeding pins 93 which are mounted in the holder plate 94 and project into the holes or throats 95 passing clear 110 through the feed block at an angle of substantially 14° from the vertical in such a manner that the pins slope toward the dies. The feeding pin holder plate 94 is mounted on a backing plate 96 having depending 115 therefrom at either end the lugs or flanges 97. The feed plate is provided near its rear end with a pair of depending lugs 98 drilled to receive a transverse arbor 99 upon which is pivoted the bell crank member or rock arm 100 which forms a connecting member between the feed plate and the parallel links and a supporting means for the feed pin backing plate.

This rock arm is substantially L-shaped in 125 elevation and has at the intersection of the two arms an enlargement forming a journal adapted for rotation about the arbor 99. The end of the shorter arm is transversely drilled to receive the arbor 101 which pivots 130

- the parallel links 84 to the rock arm. The extreme end of the longer arm is drilled transversely to receive the arbor 102 which passes through the lugs 97 of the feed pin backing plate and serves to pivotally connect that member to the rock arm. In addition the rock arm is provided with the two parallel extending lugs or stop members 103 and 104 which are adapted to alternately engage with the under surface of the feed plate and limit the amount of movement of the rock arm about its arbor 99. The three arbors 99, 101 and 102 are lubricated by means of a grease cup 105 through the grease channels 106.
- 10 In operation the feed block obtains its movement from the eccentric 74 mounted on the main drive shaft 22 which rotates continuously. The eccentric 74 and the eccentric rod 75 change the rotary motion into longitudinal motion, and thus the horizontal arm 80 of the bell crank lever 77 reciprocates in a vertical plane transmitting such motion to the link 81 and through that link to the arm 82 of the bell crank lever 78 which changes the motion from up and down to longitudinally of the feed table and the links 84 then transmit this longitudinal reciprocating motion to the feed block. The length of the stroke of the feed block, as will be noted, is readily adjustable by means of the screw 90 and the adjustable pin connection 85 at opposite ends of the link 81. Assuming the feed block to be in a position most remote from the die; a forward pull upon the links 84 will cause naturally a forward movement of the feed block, at the same time rotating the rock arm 100 about its arbor 99 until stopped by the lug 104 and projecting the feed pins 93 through the throats until their pointed ends project a substantial distance above the surface of the feed block as shown in Figure 4. The stock feed cover plate prevents any upward movement of the stock and hence the pins are projected into the bottom thereof and carry the stock forward with them. Upon reaching its closest position to the die, the motion of the feed block is arrested as the motion of the direction of the links 84 is reversed and the rock arm 100 is then rotated in the opposite direction until the stop 103 engages the under surface of the feed block, thus withdrawing the tips of the pins within the throats and releasing the stock so that the feed block can move to its rearward position where the pins can again engage the stock to move it forward.
- 40 In order to insure that the feeding pins will be projected into the material which is to be fed forward before any motion of the feed block takes place and that they be released before the return movement of the feed block begins to thus insure the exact amount of material being fed forward at each stroke, one flange 71 of the feed block
- 45 69 is provided with a friction gib 107 constrained to move therewith by the guide pins 109 and spring pressed against the vertical wall of the guide 73 by means of the coil springs 108 set in holes in the feed block. The effect of this friction gib is to retard the movement of the feed block upon the reversal of direction of movement of the links 84 at either end of the stroke in order that the feed pins may be projected above the surface of the feed block upon the initial forward movement of the links after which, when the stop 104 engages the under surface of the feed block the feed block itself will start forward. The same procedure in the reverse direction is effected upon the return movement of the block withdrawing the feed pins from the stock before moving the block in the rearward direction. Oil holes 110 are provided in the surface of the feed table to provide adequate lubrication for the ways in which the feed block travels.
- 50 In order that the machine may operate continuously without the operator keeping his foot upon the treadle 25 there is provided a lever 111 pivoted at 112 to one of the cross members of the frame of the machine and provided at the upper end with a handle 113. The lower end of the lever is constrained to move inward by means of a spring 114 and is so positioned as to rest against the end of the treadle 25 when the treadle is in its normal position as shown in Figure 1. Just below the treadle, the lever widens out on a taper as shown at 115 and again narrows down as at 116 to provide the horizontal shoulder 117. The lower end of the lever is provided with a horizontal member 118. It will be seen that upon downward pressure of the treadle the end thereof will slide along the inclined surface of the widened portion of the lever pushing it to the left against the spring 114 until the upper surface of the treadle comes below the shoulder 117 when the spring will 110 push the lever to the right and engage the shoulder 117 above the surface of the treadle and thus retain it in its lowermost position to hold the clutch engaged so that a continuous drive of the machine is effected. In order to stop the machine, it is only necessary to move the handle 113 to the right or kick the horizontal member 118 to the left to release the shoulder 117 from above the treadle and allow it to move upward under the action of its spring 26.
- 55 From the above description it will be evident that this invention provides a machine for cutting blanks from a roll of material in an entirely automatic manner requiring only the services of the operator to initially set the dies in position and adjust the length of the feed stroke to that required by the size of the die, after which attention need only be given to keeping the machine supplied with
- 60 125 130

rolls of stock and to carry away the finished blanks. With the old type of machine, as described in the first part of this specification, an operator working a day of nine hours could cut from two thousand to forty-five hundred pairs of soles or other blanks. In order to produce the maximum number of blanks the operator would have to work so rapidly that he could not carefully place the die, thus wasting a considerable amount of material. A device of this invention will cut from 120 to 180 pairs of blanks in a minute. Assuming an average speed of 140 strokes per minute, it will cut 8400 pairs per hour or approximately 75,600 in a day. By using the material in rolls of one hundred feet or more, it is obvious that there is a wastage but once in this length at the final end of each roll.

20 This machine has been illustrated in connection with dies for cutting soles, but it is to be understood that it is not limited to this particular use but may serve to cut blanks of any desired shape or size up to 25 the capacity of the machine from any sort of material which can be cut with the die.

While but one embodiment of this invention has been illustrated and described it is to be understood that the invention is only to be limited by the scope of the attached 30 claims.

Having thus described my invention what I claim as new and desire to secure by Letters Patent is:

25 1. In an attachment for dieing-out machines having a stationary die-bed support and reciprocating cutting plate in combination a die mounted on said support below said cutting plate, a feed table above the level of the cutting edge of said die, a compressible extension on said table beneath said cutting plate, a support for a roll of stock at one end of said table, reciprocating means below said table, feeding pins thereon and means to alternately project said pins above and retract them below said table.

2. In an attachment for dieing-out machines having a stationary die-bed support and reciprocating cutting plate in combination a die mounted on said support below said cutting plate, a feed table beside said die and above the cutting edge thereof, a hinged extension on said feed table adjacent said die adapted to be engaged and depressed by said cutting plate and means to normally maintain said extension in position to support the stock above said die.

3. In an attachment for dieing-out machines having a stationary die-bed support and reciprocating cutting plate in combination, a die mounted on said support having its cutting edges uppermost and adapted to cooperate with said cutting plate in cutting blanks, a stock supporting device, a feed

table between said stock support and said die, intermittent feed mechanism below the level of said feed table and means partially in the path of said cutting plate to automatically raise said stock above the level of the cutting edges of said die after each stroke of the cutting plate and before the forward movement of the feed mechanism.

4. In an attachment for dieing-out machines having a die-bed support and reciprocating cutting plate in combination, a die mounted on said support below said cutting plate, a horizontal feed table above and beside the cutting edges of said die, means supported by said table remote from said die to support a roll of stock, a feed block slidably mounted in said feed table, and means to reciprocate said block synchronously with said cutting plate. 75

5. In a stock feeding attachment for dieing-out machines, in combination a horizontal feed table, means at one end thereof to support a roll of sheet material, means spaced above said table to retain said sheet thereon, a feed block slidably mounted in said table and having its surface flush with the top thereof, means to reciprocate said block, pins extending through said block and means to project said pins above the surface of said block and into said stock before and during the forward movement of said feed block. 85

6. In a stock feeding attachment for dieing-out machines, in combination a horizontal feed table, means at one end thereof to support a roll of sheet material, means spaced above said table to retain said sheet thereon, a feed block slidably mounted in said table and having its surface flush with the top thereof, a bell crank pivotally connected to said feed block, feed pins connected to one arm of said bell crank and extending into holes passing through said feed block, reciprocating drive means connected to the other arm of said bell crank 105 adapted to project said pins above the surface of said feed block before and during the forward movement thereof and to retract them within said block before and during the rearward movement thereof to 110 intermittently feed said stock. 115

7. In a stock feeding attachment for dieing-out machines, in combination a horizontal feed table, means at one end thereof to support a roll of sheet material, means spaced above said table to retain said sheet thereon, a feed block slidably mounted in said table and having its surface flush with the top thereof, friction means to resist the sliding of said block, a bell crank pivotally connected below and to said block on an axis transverse to the direction of movement of said block, feed pins mounted on one arm of said bell crank and adapted to be projected through said feed block to at times en- 125 130

gage said stock, drive means connected to the other arm of said bell crank and means to adjust the stroke of said feed block.

8. In an attachment for dieing-out machines having a die-bed support, a reciprocating cutting plate and a drive shaft, in combination, a die mounted on said support beneath said cutting plate, a feed table beside and above the cutting edge of said die, a feed block mounted for reciprocation in and longitudinally of said feed table, a stock roll mounted on said table remote from said die, a bell crank lever pivoted to said machine and having one arm thereof associated with said feed block, a second bell crank lever, an eccentric on said drive shaft, an eccentric rod connecting said eccentric to one arm of said second bell crank lever, a link connecting the remaining arms of said bell crank levers and means to adjust the distance of one end of said link from the fulcrum of the corresponding bell crank lever.

9. In an attachment for dieing-out machines having a die-bed support, in combination a die having a cutting edge, mounted on said support, a feed table beside said die and having its surface in a plane beyond the cutting edges of said die, a hinged extension on said table adjacent said die, means to normally maintain said extension in the same plane as said table, means on the opposite end of said table to support a roll of stock to be cut, side guides on said table to guide said stock over said die and intermittent feeding mechanism associated with said table.

10. In an attachment for dieing-out machines having a die-bed support, in combination a die having a cutting edge, mounted on said support, a feed table beside said die and having its surface in a plane beyond the

cutting edges of said die, a hinged extension on said table adjacent said die, means to normally maintain said extension in the same plane as said table, means on the opposite end of said table to support a roll of stock to be cut, adjustable side guides on said table to guide said stock over said die and adjustable, intermittent, feeding mechanism associated with said table.

11. In a stock feeding attachment for dieing-out machines, in combination a feed table, a die adjacent one end thereof, a stock roll supporting means at the opposite end thereof including a pair of vertically grooved guides, a rod slidably mounted in said guides and adapted to be passed through the center of the roll of stock, a roller pivotally mounted in said guides below and parallel to said rod to support said stock roll, the upper surface of said roller being substantially in the same plane as the work surface of said feed table.

12. In an attachment for dieing-out machines having a die-bed support and reciprocating cutting plate in combination, a die mounted on said support having its cutting edges uppermost and adapted to cooperate with said cutting plate in cutting blanks, a stock supporting device, a feed table between said stock support and said die positioned above the cutting edge of said die, intermittent feed mechanism below the level of said feed table, means to automatically raise said stock above the level of the cutting edges of said die after each stroke of the cutting plate and before the forward movement of the feed mechanism and means to prevent clogging of the die by waste material.

In testimony whereof I hereunto affix my signature.

WILLIAM HUBBARD.
